UNITED STATES PATENT OFFICE.

EDWARD B. DENNY, OF NEWARK, NEW JERSEY.

APPARATUS FOR MIXING GAS AND AIR.

SPECIFICATION forming part of Letters Patent No. 416,776, dated December 10, 1889.

Application filed June 23, 1886. Serial No. 205,982. (No model.)

To all whom it may concern:

Be it known that I, EDWARD B. DENNY, a citizen of the United States, residing at Newark, in the county of Essex and State of New Jersey, have invented new and useful Improvements in Apparatus for Mixing Gas and Air, of which the following is a specification.

My invention relates to improvements in apparatus for mixing aeriform fluids, and is especially useful to me in mixing air with gasoline-gas for producing a uniform quality of gas for illuminating and heating purposes. For this purpose I provide an apparatus in which are employed two coacting meters, one for each of the fluids to be mixed, and each operated by the pressure of the fluid passing through it, in combination with devices for regulating the relative delivery movements of said meters to secure in the mixture any desired proportion of each of the fluids. To effect a perfect commingling of the separate fluids, they may be passed through a suitable mixing-chamber on their way to the point of combustion.

I will now describe more particularly my improved air and gas mixer in connection with a carbureting-machine, and point out by specific claims the matters which constitute my improvements.

Referring to the accompanying drawings, Figure 1 represents a vertical section of my improved apparatus for mixing gas and air; Fig. 2, a horizontal central section of the same; Fig. 3, a vertical central section taken through the air-meter wheel. Fig. 4 shows a vertical longitudinal section of the mixing-chamber, and Fig. 5 shows the mixer combined with the air-pump and the generator.

The meter-wheels A B may be of any construction suitable for operating in a water seal without interference with the steady flow of the fluids passing through them. They need not, however, be of the same size; but they must be connected for co-operation. As shown, they are arranged on a level side by side, and their inclosing-cases C D are preferably made to communicate at E below the water-level. One of these meter-wheels B is for gas, and the other A is for air, and the inclosing-case for each has a central inlet F for the fluid below the water-line and dis-

charge-openings G for the fluid above the water-line.

The fluid-inlet for each meter-wheel consists of a tube F, Fig. 2, fitted horizontally in the inclosing-case, and, extending into the drum, rises by a branch tube H, Fig. 3, above the water-line in a manner well known in the construction of wet-meter wheels.

The buckets I of the meter-wheels are so formed as to receive the fluid from the drum J at one end of the wheel and discharge it into the inclosing-case at the other end of the wheel. The wheels are mounted upon separate shafts K, one end of each having its bearing in a socket f, formed in the end of the inlet-tube F, while the other end of each shaft passes through a stuffing-box L of the case and is provided with a cone-pulley M outside of the case, by which the two meter-wheels are connected by a belt N, by which their co-operation is secured. These cone-pulleys are arranged in reverse positions, so that the shifting of the belt thereon will control the relative delivery movements of the gas and air

meter wheels in a manner to cause the admixture of any desired proportions of the fluids passing through them. One of the meter-cases (preferably the air-meter) is provided with a vertical tube P, Fig. 3, suitably capped at its outer end, extending from the top to near the bottom of the case, by which the water is introduced and the pipe sealed therein against the escape of the fluid. As these meter-wheel cases are made to communicate, both are thereby filled through the same tube, the level of the water in both being gaged by a suitable sight-gage, petcock, or plug Q. At the bottom of each meter-case there is a screw-plug R, by which the water may be drawn off. At the meeting sides of the meter-cases there are openings or perforations G, Fig. 1, placed above the water-line, through which the fluids pass to their meeting-point in the delivery-pipe.

As shown, a mixing-chamber S connects the meter-cases at their fluid-outlet openings G, into which the fluids are caused to pass to insure their perfect commingling. This mixing-chamber is filled with fibrous material and is of such construction as to cause the fluids to enter and traverse its passages and

to escape therefrom at the outlet T, and thereby break any currents in the flow to the supply-pipe, as shown in Fig. 4. The placing of the two meter-wheels on the same level 5 makes it necessary to have but one water-filler and one water-gage, insures the same relative discharge from each meter, gives a convenient placing for the mixing-chamber, and avoids the danger which would attend the 10 placing of a water filler or gage on the gas-meter case.

This apparatus may be used for mixing any fluids that can be delivered to it under pressure sufficient to operate the wheels in 15 the water seal, and it will be understood that the pressure of the fluids alone operates the apparatus whether the meters be wet or dry.

I prefer to make the air-meter wheel smaller than the gas-meter wheel, so as to leave a 20 space in the case of the latter for the introduction and sealing of the water-filling pipe, but to obtain the more important advantage of permitting the use of comparatively small cone-pulleys, because in the mixture of gaso-line-gas with air the maximum quantity of 25 air required may be obtained by placing the belt upon the fastest feed of the air-wheel, while by placing the belt upon the opposite ends of the cone-pulleys a smaller quantity 30 of air is obtained, and thus the minimum quantity of air is added to the mixture when the gas requires the least dilution.

The meter-wheels are filled with the sealing-liquid to the gage, and the fluids to be 35 mixed are introduced into their respective meter-wheels under pressure and operate them in passing through the buckets thereof, filling the spaces of the inclosing-cases above the water seal under the same pressure, and 40 passing therefrom through the case-openings into the mixing-chamber, and thence to the outlets under the same pressure. When an outlet is made, the wheels will revolve to supply the outflow, and the relative delivery 45 movements of the wheels will be determined by the position of the belt upon the cone-pulleys, which of course will determine the relative proportions of the fluids passing to the 50 mixing-chamber. If the volume of one of the fluids is in excess of the requirements, then the relative proportions may be easily 55 and quickly changed by shifting the belt upon the cone-pulleys. More particularly, the position of the belt upon the cone-pulleys shown will give what may be called the "fastest feed"—that is, it will give a much 60 greater volume of air than gas. By changing the belt to the other end of the cones the proportion of gas would greatly exceed that of the air, and by shifting the belt into intermediate grooves of the cone-pulleys any desired proportions of the fluids may be obtained to give the desired mixture.

In using my gas and air mixer with what 65 is known as a "gasoline-gas machine" I have no difficulty in obtaining a uniform mixture of the gas and air whether the pressure upon

the two fluids at their entrance into the apparatus is equal or unequal, since both of the fluids must pass through the apparatus, 70 wherein any unequal pressure is neutralized by means which make the meter-wheels co-operative in their operation to regulate the proportions of gas and air. This co-operating action of the meter-wheels acts to steady 75 the pressure of the outflowing mixture even though one or both of the fluids may be received under an unsteady or variable pressure.

I prefer to use the cone-pulleys as the 80 means for regulating the relative delivery movements of the meter-wheels, because they admit of being connected for operation with the least possible friction, because their connecting-belt can be adjusted easily and 85 quickly, because it is comparatively inexpensive in construction and adds little to the weight of the meter-shafts, because they admit of endwise play of the meter-wheel shafts to avoid endwise friction in their journal- 90 bearings, and because it is an important matter to avoid all possible friction, which causes an unsteady pressure in the outflow of the mixture, which would result from the use of metal gearing, which is liable to expand and 95 contract and to become clogged and to bind.

I prefer to use separate and independent meter-wheel cases, because the fluid from each can be delivered therefrom under pressure in streams into the fibrous material of the 100 mixer, and thereby more perfectly effect their commingling, and because it practically isolates the gas from the air until they enter the mixing-chamber, and thereby prevents the mixing operation from taking place 105 within the meter-wheel closures, and because the gas is excluded from the closure of the air-wheel, which contains the water-filler and the water-gage.

I find it important to arrange the water-filler P and gage Q within the closure of the air-meter wheel, so that if either of them should leak the escaping fluid would do no harm.

In Fig. 5 I have shown my gas and air 115 mixer combined with an air-pump and generator of what is known as a "gasoline-gas machine," in which U is the air-pump, which is driven by the weight V and its suspending-cord acting in the usual manner upon the drum of the pump-shaft. The generator 120 W may be buried in the earth outside of the house, and is provided with a filling-pipe a, the air-supply pipe b connecting with the pump and with the meter-wheel tube F by pipe b², and the gas-delivery pipe c connecting with the gas-meter-wheel tube F.

I find in gas-mixing machines that two connected meter-wheels have been used in independent water-containing chambers for mixing gases, in which one of said wheels transmits a positive motion to the other and in which gearing devices are employed for transmitting this positive motion, operating so that

the relative speed of the two meter-wheels and the quantity of gases of different consistencies measured by either of them may be varied by adjusting the gearing of the wheel devices for regulating the delivery movements. I find, however, that to maintain the same relative discharge of gas and air from independent water-containing chambers by coacting meter-wheels it is important to produce satisfactory results that the speed-regulating device be of the simplest construction and under convenient control, whereby the minimum quantity of air may be added to the mixture when the gas requires the least dilution. For this purpose I employ the well-known belt-connected cone-pulleys, and in such use I find much better results and advantages than can be obtained from gearing, for the reasons which I have hereinbefore stated. As compared with gearing, the cone-pulley device for regulating the delivery movements of both meter-wheels to obtain in the mixture any desired proportion of each of the fluids affords the important advantage of being easily and quickly adjusted, because to obtain the maximum quantity of air for the gas the belt need only be placed upon that end of the cone of the air-wheel shaft which gives the fastest feed. Then when a smaller quantity of air is required the belt can be quickly changed to the opposite ends of the cone-pulleys and the gas is least diluted. Added to this facility for adjustment are the advantages of lightness and freedom from binding and from friction incident to cog-wheels.

The provision of meter-wheels of unequal capacity operating within communicating chambers of equal capacity gives the advantage of using comparatively small cone-pulleys for regulating the speed of the wheels, while the communicating chambers permit the gas-chamber to be supplied with water from the air-chamber.

As shown in Fig. 2, the small end of the cone is placed inward upon the shaft containing the small air-wheel, while the large end of the other cone-pulley is placed inward upon the shaft of the large gas-wheel, and this is the arrangement which gives the minimum quantity of air when the gas requires the least dilution, and which permits the air-wheel to be made smaller than the gas-wheel, and is thereby more easily operated by the air-pressure, because it has less resistance in moving through the water.

The communication of the water-containing chambers insures the same level in each chamber at all times, and it is this provision which renders certain the relative capacity of the wheels; but such relative capacity is only important and advantageous in connection with the regulating function of the belt-connected cone-pulleys, which co-operate with the meter-wheels in the way described.

I claim—

1. In apparatus for mixing air and gas, the combination of the chambers having equal capacity for containing water with meter-wheels of unequal capacity arranged therein upon independent shafts and the belt-connected cone-pulleys placed upon the shafts of the meter-wheels, substantially as described, for the purpose specified.

2. The mixing apparatus for gas and air herein described, consisting of the two chambers of equal capacity for containing water, having the communicating openings E and G, the meter-wheels of unequal capacity arranged within said chambers upon independent shafts, the chamber C, having the wheel of least capacity, having also the water-sealed filling-tube, and the belt-connected cone-pulleys arranged upon said shafts in reverse relation to each other and to the meter-wheels, for the purposes stated.

3. The combination, in a gasoline-gas machine, of the independent chambers for containing water, the meter-wheels arranged therein, the generator, the air-pump, a mixer placed between said chambers, and the belt-connected cone-pulleys for regulating the speed of the meter-wheels for delivering both air and gas in proper quantities into the said mixer, substantially as described.

4. In a machine for mixing air and gas, the combination of the independent chambers of equal capacity adapted to contain water with air and gas meter wheels operating therein having unequal capacity, the meter-wheel of least capacity being arranged in the air-chamber C, and the cone-pulleys arranged in relation described upon the shafts of said wheels, for the purpose stated.

5. In a machine for mixing air and gas, the independent water-containing chambers having communication below the water-line, communication above the water-line, and a mixing-chamber covering said upper communications, in combination with an air and a gas meter wheel arranged upon independent shafts within said chambers, as described and shown.

6. In a machine for mixing air and gas, the water-containing chambers and the air and gas meter wheels arranged therein upon independent shafts, in combination with means for regulating the operation of said wheels, consisting of the belt-connected cone-pulleys placed upon the shafts of said meter-wheels, substantially as described, for the purpose specified.

In testimony whereof I have hereunto set my hand in the presence of two subscribing witnesses.
